UNITED STATES PATENT OFFICE.

ELIAS A. JUKES, OF ST. CATHARINES, ASSIGNOR OF ONE-HALF TO ARTHUR JUKES JOHNSON, OF TORONTO, ONTARIO, CANADA.

AUTOMATIC CUT-OFF FOR GAS-BURNERS.

SPECIFICATION forming part of Letters Patent No. 340,951, dated April 27, 1886.

Application filed July 3, 1885. Serial No. 170,608. (No model.)

To all whom it may concern:

Be it known that I, ELIAS ARTHUR JUKES, of the city of St. Catharines, in the county of Lincoln, in the Province of Ontario, Canada, 5 have invented an Improved Cut-Off for Gas-Burners, of which the following is a specification.

The object of the invention is to design an automatic cut-off for gas-burners which, while 10 operated by the gas-jet, will not in any way affect the appearance of the flame; and it consists, essentially, of a metal tube placed parallel with and sufficiently close to the burner that the heat from the gas-jet will act directly 15 upon the tube, causing the same to expand and actuate a pivoted lever arranged to come in contact with a notch or projection formed on a cut-off valve or its attachment, so that when the light is extinguished the valve is 20 closed by the lever upon the cooling and consequent contraction of the metal tube.

Figure 1 is an enlarged sectional view showing a gas-burner provided with my improved automatic cut-off. Fig. 2 is a perspective outside view of the same on a reduced scale. Fig. 25 3 is a perspective view of cut-off valve.

The primary object of all cut-offs for gas-burners is to so arrange the parts that upon the flame being extinguished a valve shall be 30 closed by the contraction of the parts previously expanded by the heat of the flame; but in all such automatic cut-off valves with which I am familiar the part to be acted upon by the flame is carried through the said flame, 35 which is thereby caused to burn unevenly or horizontally above the burner, which is quite as objectionable, to remedy which defect is the primary object of my invention, while at the same time I secure an automatic cut off 40 simpler in construction and more effective in operation than any other with which I am familiar.

In the drawings like letters of reference indicate corresponding parts in each figure.

45 A is the burner proper, which I provide, preferably, with two inlets, *a* and *b*, so that the burner may be either attached to a vertical or horizontal pipe. It will of course be understood that the inlet not used will be 50 plugged.

On one side of the burner A, I form a projection, *d*, in which I support, as indicated, a metal tube, B. From the upper end of this tube B a metal pendant, C, extends to a point opposite to the collar D, which is fixed to the 55 burner A, as indicated. A lug, *e*, projects from the collar D through a slotted passage-way in the tube B, forming a pivot-support for the lever E, contained within the tube B, as indicated. This lever E is also pivoted, as 60 indicated, on the end of the pendant C.

F is a cylindrical cut-off valve passing through the burner A, and having an aperture, *f*, through it to correspond with the passage-way *g* through the burner. It is of course 65 intended that this valve F shall be packed or otherwise made gas-tight; but at the same time it is intended to move freely longitudinally through the burner.

In order to prevent the valve F revolving, 70 and thereby alter the position of its aperture *f*, I provide a pin, *h*, fixed at one end to the burner and passing through a slot, *i*, made in the cut-off valve F.

H is a trip or handle pivoted to the end of 75 the valve F, and having a notch, *j*, made on its top side.

I is a spring arranged to come in contact with a pin or projection connected to the cut-off valve F. The spring I is arranged to 80 press the valve F in the direction indicated by arrow, so that when not otherwise acted upon the valve F will be held as indicated in Fig. 1, so that its aperture *f* shall be immediately in the passage-way *g*.

85 It will of course be necessary to provide a suitable stop to prevent the spring carrying the valve too far in the direction indicated. This stop may be in the form of a pin, *k*, or other suitable means might easily be devised. 90

As Fig. 1 represents the burner lighted, it of course follows that the tube B is expanded, and consequently, as the lever E is pivoted on the end of the pendant C, which is moved upwardly by the expansion of the tube B, and 95 is also pivoted on the lug E, secured to the burner A by the collar D, which is not moved by the expansion of the tube B, the lever E is carried from its initial position, indicated by dotted lines, into the position it is shown 100

by full lines, where its end fits behind the notch *j*, the trip *H* being actuated upwardly as well as outwardly by the spring *I*.

Should the flame from the burner *A* be blown or otherwise accidentally put out, the tube *B* will naturally contract as it cools. Consequently the lever *E* will be pushed back into its initial position, carrying with it the valve *F*, thereby closing the passage-way *g* and effectually cutting off the gas from the burner, should it not have been previously turned off by the ordinary gas-cock.

As the spring *I* is, as before stated, designed to hold the trip *H* upwardly, and thereby keep the notch *j* in contact with the end of the lever *E*, it follows that so long as the trip *H* is not touched the valve *F* will be held closed by the lever *E* and no gas will escape, nor can the burner be lighted until the trip *H* is pressed down so as to clear its notch *j* from the end of the lever *E*, when the action of the spring *I* will cause the valve to move back in the direction indicated by arrow until the aperture *f* comes opposite to the passage-way *g*.

25 In order to insure the immediate and rapid expansion of the tube *B*, I provide a small jet, *m*, which will of course light with the burner, and by acting directly on the tube *B*, as indicated, will materially assist in its expansion, 30 which assistance will be of considerable advantage should the burner when lighted be turned down so low as not to produce sufficient heat for the rapid expansion of the tube *B*.

The drawings represent the burner *A* and 35 tube *B* contained within a casing, *J*. This casing is not necessary for the satisfactory working of my automatic cut-off, but as it might be ornamented and the tube and burner arranged within it so as to give the appearance 40 merely of a single burner, it is to that extent important.

What I claim as my invention is—

1. The combination, with the burner *A*, of a tube, *B*, supported substantially parallel with 45 and in proximity thereto, the cut-off valve *F*, and lever *E*, pivoted to the burner connected with said tube *B* and engaging with said cut-off valve, whereby the contraction of the tube *B* will actuate said valve to cut off the supply 50 of gas to the burner, substantially as specified.

2. A burner, *A*, and a tube, *B*, supported substantially parallel with and in proximity to the burner *A*, a pendant, *C*, attached to the

tube *B* and forming a support for the pivot connecting it to the lever *E*, in combination 55 with said lever, the lug *e*, attached to the burner *A* and forming a support for the pivot connecting it to the lever *E*, and a cut-off valve connected with said lever, substantially as and for the purpose specified. 6c

3. A burner, *A*, and a tube, *B*, supported substantially parallel with and in proximity to the burner *A*, a lever, *E*, provided with two pivots, one connecting it to the tube *B* and the other to the burner *A*, in combination 65 with a cut-off valve, *F*, situated as specified and provided with a notch or projection to connect it with the lever *E*, substantially as and for the purpose specified.

4. A burner having passage-way *g*, and a 70 cock-passage at right angles thereto, a cut-off valve arranged in said cock-passage and provided with an aperture, *f*, to correspond with the passage-way *g*, and a slot, *i*, to form a passage-way, and the pin *h*, in combination with 75 the tube *B*, a spring, *I*, arranged to actuate the cut off valve *F*, the lever *E*, trip *H*, and intermediate connections, substantially as described, between said tube, lever, and burner, said valve being also provided with a stop for 80 limiting the movement thereof, substantially as and for the purpose specified.

5. The combination, with a gas pipe and burner, of a cut-off valve, the tube *B*, lever *E*, a trip, *H*, pivoted to said valve and provided 85 with a notch, *j*, intermediate connections, substantially as described, between said tube, lever, and burner, and a spring, *I*, arranged to actuate the valve *F* outwardly and the trip *H* upwardly, substantially as and for the pur- 90 poses specified.

6. A burner, *A*, a tube, *B*, supported substantially parallel with and in proximity thereto, a cut-off valve, *F*, the lever *E*, pivoted to the burner connected with tube *B* and engaging 95 with said cut-off valve, combined with the jet-tube *m*, extending from the burner adjacent to the flame thereof, and outside of and in close proximity to said tube, substantially as and for the purpose specified.

Toronto, June 26, 1885.

E. A. JUKES.
